MAGNETIC TRANSLATING DEVICE

Benjamin B. Bauer, Chicago, Ill., assignor, by
mesne assignments, to Shure Brothers, Incorporated,
Chicago, Ill., a corporation of Illinois

Continuation of application Serial No. 424,282,
December 24, 1941. This application December
23, 1943, Serial No. 515,463

17 Claims. (Cl. 175—339)

1

The present invention relates to electromagnetic translating devices of the type having a movable armature and has particular application to devices involving voice or other variable currents. In such an electromagnetic translating device, the translating action fundamentally involves the variable reaction between a substantially constant and variable magnetic fields. The constant field may be obtained by electromagnets or more commonly by permanent magnets. The variable field may be obtained by variable currents acting on an electromagnet or by mechanical motion of an armature, depending upon the direction in which translation occurs.

Both the variable and constant fields have magnetic circuits and for maximum efficiency have conflicting requirements. Thus for high efficiency, the constant field magnetic circuit must have certain portions, notably the pole pieces defining air gaps, operate at high flux densities. The variable magnetic fields are generally weak in comparison to the constant field and high efficiency demands that the magnetic circuit have high permeability. The art has generally provided common paths for a substantial portion of the magnetic circuit of each system particularly at those portions of the constant field circuit operating at high flux densities. Since iron or other ferromagnetic material operating at high flux densities has low permeability it is clear that the efficiency of the variable field part of the translating device and hence the translating device itself suffered.

In general, the art has provided constructions which have aggravated the above problem. Thus the disposition of an armature between the arms of a U-shaped magnet is common, the armature generally extending back from the poles toward the central part of the magnet. Such a construction not only promotes flux leakage but at the same time the flux density in the armature tends to reduce its permeability and thus renders it less efficient, for use with weak variable magnetic fields.

This invention contemplates the provision of minimum paths common to the constant and variable magnetic field circuits. Since translation involves the interaction between such two fields, complete segregation is impossible. However, this invention contemplates reducing the common paths substantially to the air gap portions of the system, including of course any intervening armature. In general this is accomplished by providing two substantially separate

2

ferromagnetic circuits which interlink at the air gaps and are otherwise substantially complete in themselves.

Referring now to the drawings:

- 5 Figure 1 is a diagrammatic isometric illustration to show the magnetic circuits;
Fig. 1a shows a modified coil construction for
Fig. 1;
Fig. 2 is a view in a diagrammatic form similar
10 to Fig. 1 but showing a modification;
Fig. 3 is a plan view of a translating device;
Fig. 4 is a section on line 4—4 of Fig. 3;
15 Figs. 5 and 6 are details of the armature bearing magnetic circuit with coils shown diagrammatically; and
Fig. 7 is a section on line 7—7 of Fig. 4 with the
voice current coil omitted and showing in more
or less diagrammatic form some magnetic lines
of force.
- 20 Referring first to Fig. 1 a permanent magnet
10 having poles 11 and 12 is provided. This
magnet is preferably of any alloy such as
"Alnico," having high coercive force and generating
a relatively intense field. Pole pieces 14
25 and 15 are disposed on poles 11 and 12 of the
magnet and are shaped to provide pole faces 16
and 17. Pole face 16 may be shaped to provide
a pair of recesses 18 and 19 and leave three
projecting parts 20, 21 and 22. Similarly pole
30 face 17 has recesses 24 and 25 with projecting
parts 26, 27 and 28. For economy in manufacture,
pole pieces 14 and 15 may be substantially alike.
35 Projections 21 and 27 in this figure are
spaced apart to form an air gap 30 therebetween
in which translation may occur. The remaining
pairs of projections 20 and 26; 22 and 28 are
kept separated by non-magnetic spacers 32
and 33.

Tightly clamped between the non-magnetic
40 spacers is a generally E-shaped member 35 of soft steel or other ferromagnetic material. Member 35 has end arms 36 and 37 with an intermediate arm 38 all connected by a body portion 39. The precise shape of the various arms
45 is unimportant. End arms 36 and 37 are tightly gripped between spacers 32 and 33. Center arm 38 extends into air gap 30 and has sufficient elasticity to vibrate therein. Normally, the three arms are symmetrical with respect to the median plane between the opposed pole faces. It is preferred to have end arms 36 and 37 about equal in width and each have a width about half that of the center arm or armature 38.

Surrounding armature 38 is a voice current
50 coil 40 and within this coil armature 38 is free

to vibrate. A bolt 41 may pass through body portion 39 to anchor member 35 and restrict vibration to armature 38.

The general paths of the lines of magnetic force are suggested by heavy lines for the constant field and light lines for the variable field. Thus, as a rule, parts 43, 44, 45 and 46 bordering on the recesses have low field density from magnet 10. By providing recesses, the reluctance between opposing pole piece surfaces is increased. Obviously these recesses may be made as large or small as desired and may even be omitted. The clamped ends of arms 36 and 37 between the pole pieces will normally provide a substantial reduction in reluctance for the permanent field flux so that even without recesses, there would be a tendency for the field to divide somewhat as shown. The variable flux goes from the ends of arms 36 and 37 through spacers 32 and 33 to parts 43, 44, 45 and 46 and thence to central projections 21 and 27 through air gap 30 and armature 38.

Movement of the armature in the air gap either causes or results from (depending upon the direction of translation) the variable reaction between two magnetic fields. The main field has part of the lines of force passing through the armature magnetic circuit and during translation the flux distribution in the gaps is altered. Paths of comparatively low reluctance are provided for the main flux between the pole pieces. The variable flux path through member 38 has low reluctance, generally avoids highly saturated parts and thus has high permeability throughout most of the path. Furthermore, member 38 has most of its bulk out of the space enclosed by the main field structure and thus leakage is reduced to a minimum.

Armature 38 may have an apertured tip 48 for receiving or transmitting vibratory motion. Thus a diaphragm or stylus or other means may be operatively connected thereto.

It is evident that the secondary magnetic circuit, here the E-shaped member including the armature furnishes a substantially separate complete path for the variable or what may be termed the alternating flux. Except for the gaps and the armature tip in air gap 30, the two circuits are quite separate.

The disposition of member 38 outside of the space enclosed by the main magnetic field structure exposes member 38 and voice coil 40 to stray fields, unless suitable shielding is provided. In order to eliminate any hum or noise due to stray fields, coil 40 may be replaced by two coils 40' and 40'' so connected as to be magnetically opposed, and disposed on parts 39' and 39'' of body part 39, as shown in Fig. 1a. For voice currents, the two coils are the equivalent of single coil 40 since the opposed fields go into center leg 38. However, any stray fields particularly along the direction of arms 36 and 37 will result in equal and opposite potentials. Thus hum may be easily eliminated.

Referring now to Fig. 2, a modified form is shown wherein member 135 has central arm 138 tightly clamped between non-magnetic spacers 132 and 133 disposed between parts 121 and 127 of pole pieces 111 and 112. Arms 136 and 137 operate in air gaps 130 and 130' between pole parts 120, 126 as one pair and 122 and 128 as the other pair. Instead of one coil for voice currents, a pair of coils 140 and 140' are disposed over arms 136 and 137, the arms being free to vibrate therein. The coils are connected as

shown so that corresponding coil ends have opposite magnetic polarity. A torsion rod 150 is suitably anchored to central arm 138 so that as arms 136 and 137 vibrate, rod 150 is vibrated torsionally. A stylus 151 may be carried by rod 150 for phonograph recording or reproduction. If desired a diaphragm may be actuated. It is understood that torsion rod 150 may be supported in bearings. This construction has hum buck properties similar to the modified construction of Fig. 1a.

The coils may be connected so that the current flow is in the same direction in both and will result in arms 136 and 137 being urged in the same direction. Obviously only one coil may be disposed over central arm 138 in that case.

Referring now to Figs. 3 to 7 inclusive, a magnet 210 having pole pieces 214 and 215 is retained in assembled relation by non-magnetic bolt 201. Bolt 202 extends through both pole pieces to engage a massive base 203. Pole pieces 214 and 215 have pole faces 216 and 217. The center parts 221 and 227 of the pole faces define an air gap 230 while the end parts 220, 226, 222 and 228 are spaced apart by non-magnetic spacers 232 and 233. Gripped between non-magnetic spacers 232 and 233 is a member 235 of a generally C-shape having arms 236 and 237 terminating in inturned tip portions 236' and 237'. This may be relatively thick to reduce reluctance. A central arm 238 (preferably separate to permit insertion of a wound coil) may be riveted to body portion 239 to make a generally E-shaped body. It is understood that the pieces as shown in Figs. 5 and 6 are made of ferromagnetic material as soft steel. A voice current coil 240 wound on a suitable bobbin is disposed around arm 238 within arms 236 and 237 and may be secured to base 203 in a manner to permit free vibration of arm 238. Body portion 239 is bolted at 241 to a part of base 203. Tip 248 of arm 238 has a non-magnetic rod 251 secured thereto and this rod extends down through an aperture 252 in pole piece 215 to the apex of a diaphragm 253 suitably carried by base 203. An insulating block 255 carried by bolts 241 may support voice coil terminals 255.

In order to protect against stray fields, a hum buck coil 240' is provided. This coil is preferably disposed to enclose arms 236 and 237 and voice current coil 240. The hum buck coil 240' may have relatively few turns, as compared to coil 240. The two coils 240 and 240' are connected in series and the polarity is such that the magnetic fields of the two coils oppose each other. This is shown diagrammatically in Fig. 6.

Tips 236' and 237' function to reduce the air gaps extending toward arm 238 and thus reduce the reluctance of the variable field path throughout member 235 and arm 238. Since these tips have air gaps (in the main circuit) on opposite sides transverse to the planes of the arms; i. e. toward pole faces 216 and 217 the reluctance of the main field path is kept at a predetermined value and controlled.

Thus referring to Fig. 7, the reluctance of the magnetic circuit containing the armature is low and the lines of force may be imagined as drawn. The reluctance of the main magnetic circuit must be considered generally along lines connecting the main pole pieces; i. e. extending up and down Fig. 7 and is maintained at a desirable value all the time.

Thus as the armature goes down in Fig. 7, the variable flux density is increased below the armature and decreased above the armature. As the

armature goes up the reverse occurs. The reluctance for the constant field remains more or less constant during armature travel. When used to translate armature movements into currents, the permanent magnet supplies both the constant and variable fields. It is understood that the variable fields may be either due to a variation in field strength or variation in path or both.

Thus in the various forms of the invention, the constant and variable fields have their magnetic circuits with minimum common paths.

This application is a continuation of my co-pending application Serial No. 424,282, filed December 24, 1941, now abandoned.

I claim:

1. In a translating device, the combination of a constant flux magnetic member having opposed pole faces spaced apart to form a space therebetween, a variable flux magnetic member having a plurality of end portions extending in a generally similar direction and an intermediate portion connecting said end portions together, said intermediate portion being disposed outside of the volume encompassed by said constant flux magnetic member and said end portions being disposed in said space and in adjacent spaced relation to said pole faces to form with said constant flux magnetic member one or more variable flux ferromagnetic circuits which are substantially closed except for the spaces between said end portions and said pole faces, one of said end portions in said ferromagnetic circuit or in each of said ferromagnetic circuits being vibratable in said space to form an armature, means for substantially fixing the other of said end portions in said ferromagnetic circuit or each of said ferromagnetic circuits in position in said space out of ferromagnetic contact with said pole faces, and a winding surrounding a portion of said variable flux magnetic member.

2. A construction as claimed in claim 1, in which the pole faces of the constant flux magnetic member are in substantially parallel spaced relation to each other and the end portions of the variable flux magnetic member project into the space between said pole faces and at least one of the pole faces has projecting surfaces at the portions thereof opposed to said end portions, whereby the magnetic reluctance between said pole faces is lower at said projecting portions than at the spaces between said portions.

3. A construction as claimed in claim 1, in which the space between the pole faces of the constant flux magnetic member is throughout of substantially uniform length in the direction of the flux path at said space and the end portion or portions of the variable flux magnetic member define the paths of low magnetic reluctance between said pole faces.

4. A construction as claimed in claim 1, in which the end portions of the variable flux magnetic member are thin and flat and, in the at rest position of the vibratable end portion, all of said end portions are located in substantially the same plane.

5. A construction as claimed in claim 1, in which the pole faces of the constant flux magnetic member are in substantially parallel spaced relation to each other and the end portions of the variable flux magnetic member project into the space between said pole faces and, in the at rest position of the vibratable end portion or portions, are arranged to lie in a plane substantially midway between and parallel to said pole faces.

6. A construction as claimed in claim 1, in which a coil is wound about a portion of the variable flux magnetic member disposed outside the volume encompassed by the constant flux magnetic member.

7. A construction as claimed in claim 1, in which a voice coil and a hum buck coil are wound about a portion of the variable flux magnetic member disposed outside the volume encompassed by the constant flux magnetic member.

8. In a translating device, the combination of a constant flux magnetic member having a pair of opposed pole faces spaced apart to form a single space therebetween, a variable flux magnetic member having a body portion and a plurality of spaced apart substantially flat arms lying in substantially the same plane and extending from said body portion in a generally similar direction, means for supporting said variable flux magnetic member with said body portion disposed outside of the volume encompassed by said constant flux magnetic member and the free ends of said arms disposed in said space and in adjacent spaced relation to and out of ferromagnetic contact with said pole faces to form with said constant flux magnetic member one or more variable flux ferromagnetic circuits which are substantially closed except for the spaces between said arm ends and said pole faces, at least one of said arms in said ferromagnetic circuit or in each of said ferromagnetic circuits being vibratable in said space, and a winding surrounding a portion of said variable flux member.

9. In a translating device, the combination of a constant flux magnetic member having a pair of opposed pole faces spaced apart to form a single space therebetween, a variable flux magnetic member having a body portion and a plurality of spaced apart substantially flat arms lying in substantially the same plane and extending from said body portion in a generally similar direction, means for supporting said variable flux magnetic member with said body portion disposed outside of the volume encompassed by said constant flux magnetic member and the free ends of said arms disposed in said space and in adjacent spaced relation to and out of ferromagnetic contact with said pole faces to form with said constant flux magnetic member one or more variable flux ferromagnetic circuits which are substantially closed except for the spaces between said arm ends and said pole faces, at least one of said arms being fixed in said space and the remainder of said arms being vibratable in said space, and a winding surrounding a portion of said variable flux member.

10. In a translating device, the combination of a constant flux magnetic member having opposed pole faces separated to provide a space therebetween, a variable flux magnetic member having a main body portion disposed outside the volume encompassed by said constant flux magnetic member and a plurality of end portions disposed in said space, means for maintaining said end portions in spaced relation to and out of ferromagnetic contact with said pole faces, whereby said variable flux magnetic member forms with said constant flux magnetic member one or more variable flux ferromagnetic circuits which are substantially closed except for the spaces between said end portions and said pole faces, at least one end portion of said ferromagnetic member being vibratable to form an armature, and a winding surrounding a portion of said variable flux magnetic member.

11. In a translating device, the combination of a constant flux magnetic member having opposed pole faces separated to provide a space therebetween, a variable flux magnetic member having a main body portion disposed outside the volume encompassed by said constant flux magnetic member and a plurality of end portions disposed in said space, means for maintaining said end portions in spaced relation to and out of ferromagnetic contact with said pole faces, whereby said variable flux magnetic member forms with said constant flux magnetic member one or more variable flux ferromagnetic circuits which are substantially closed except for the spaces between said end portions and said pole faces, at least one end portion of said ferromagnetic member being vibratable to form an armature, and a winding surrounding a portion of said variable flux magnetic member, the arrangement being such that the variable flux path in the constant flux magnetic member is shorter than the variable flux path in the variable flux magnetic member.

12. In a translating device, the combination of a constant flux magnetic member having opposed pole faces separated to provide a space therebetween, a variable flux magnetic member having a main body portion disposed outside the volume encompassed by said constant flux magnetic member and a plurality of end portions disposed in said space, means for maintaining said end portions in spaced relation to and out of ferromagnetic contact with said pole faces, whereby said variable flux magnetic member forms with said constant flux magnetic member one or more variable flux ferromagnetic circuits which are substantially closed except for the spaces between said end portions and said pole faces, at least one end portion of said ferromagnetic member being vibratable to form an armature, and a winding surrounding a portion of said variable flux magnetic member, the arrangement being such that the constant flux path within the variable flux magnetic member is substantially confined to said end portions of said variable flux magnetic member.

13. In a translating device, the combination of a constant flux magnetic member having opposed pole faces spaced apart to form a space therebetween, a substantially U-shaped, variable flux magnetic member having the end portions thereof disposed in said space and in adjacent spaced relation to said pole faces and the intermediate portion thereof disposed outside of the volume encompassed by said magnetic field member, one of said end portions being vibratable in said space, means for fixing the other of said end portions in

said space and out of ferromagnetic contact with said pole faces, and a winding surrounding a portion of said variable flux magnetic member.

14. In a translating device, the combination of a constant flux magnetic member having opposed pole faces spaced apart to form a space therebetween, a substantially E-shaped variable flux magnetic member having a body portion and spaced apart arms extending from said body portion, said body portion being disposed outside of the volume encompassed by said constant flux magnetic member and the end portions of said arms being disposed in said space and in adjacent spaced relation to said pole faces to form with said constant flux magnetic member two variable flux ferromagnetic circuits which are substantially closed except for the spaces between said arm end portions and said pole faces, one of said arms in each of said ferromagnetic circuits being vibratable in said space, means for fixing the end portion of the other of said arms in each of said ferromagnetic circuits in said space and out of ferromagnetic contact with said pole faces, and a winding surrounding a portion of said variable flux magnetic member.

15. A construction as claimed in claim 14, in which the middle arm of the E-shaped magnetic member is vibratable and the outer arms are substantially fixed in position.

16. A construction as claimed in claim 14, in which the middle arm of the E-shaped magnetic member is substantially fixed in position and the outer arms are vibratable.

17. A construction as claimed in claim 14, in which the middle arm of the E-shaped magnetic member has a width substantially equal to the sum of the widths of the outer arms thereof.
